Primary Examiner — Jeffrey D Asch*(74) Attorney, Agent, or Firm* — Banner & Witcoff, Ltd.(57) **CLAIM**

The ornamental design for a handset, as shown and described.

DESCRIPTION

FIG. 1 is a perspective front view of a handset showing our new design;
FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines of the handset in FIGS. 1-7 and the unshaded regions within the broken lines show portions of the handset and form no part of the embodiment in which they are shown.

1 Claim, 5 Drawing Sheets(56)
